(57) **CLAIM**

The ornamental design for a vending machine, as shown and described.

DESCRIPTION

FIG. 1 is a top, front, and right side perspective view of a vending machine showing our new design.

FIG. 2 is a rear and left side perspective view thereof.

FIG. 3 is a front elevation view thereof.

FIG. 4 is a right side elevation view thereof.

FIG. 5 is a left side elevation view thereof.

FIG. 6 is a rear elevation view thereof; and,

FIG. 7 is a top plan view thereof.

In FIGS. 1, 4, 5, and 7, circular openings arranged in an array located laterally in a central portion of the top of the vending machine are shown in broken lines. Broken lines represent portions of the vending machine that form no part of the claim.
